UNITED STATES PATENT OFFICE.

LOUIS C. KOHLER, OF MILWAUKEE, WISCONSIN, ASSIGNOR OF ONE-HALF
TO LORENZ KRESS, JR., OF MILWAUKEE, WISCONSIN.

BRAKE-OPERATING MEANS.

SPECIFICATION forming part of Letters Patent No. 789,551, dated May 9, 1905.

Application filed September 6, 1904. Serial No. 223,376.

To all whom it may concern:

Be it known that I, LOUIS C. KOHLER, residing in Milwaukee, in the county of Milwaukee and State of Wisconsin, have invented new and useful Improvements in Brake-Operating Means, of which the following is a description, reference being had to the accompanying drawings, which are a part of this specification.

This invention relates to brake-operating means, and has for its object to provide a means for applying the brakes of moving vehicles by utilizing the momentum of the vehicle as a braking force.

A further object of this invention is to provide a roller adapted to be brought into contact with one of the wheels of the vehicle to receive rotary motion therefrom and cause it to ride on a bearing-lever and wedge its way between said bearing-lever and the wheel-tread to produce a movement of the bearing-lever, and thereby apply the brakes.

A further object of this invention is to provide such a device as above mentioned with a clutching means between the wheel-engaging portion and the bearing-lever-engaging portion which will lock together such engaging portions until a predetermined resistance is met with by the bearing-lever-engaging portion, when such engaging portions are disconnected and the wheel-engaging portion is free to move independently of the other engaging portion.

With the above and other objects in view the invention consists in the devices and parts and combinations of parts and their equivalents, as hereinafter set forth.

Referring to the accompanying drawings, in which like characters of reference indicate the same parts in the several views, Figure 1 is a side elevation of one end of a car-platform with its truck, parts being broken away for clearness of illustration. Fig. 2 is a bottom view thereof. Fig. 3 is an end elevation of the wheel-engaging rollers and their co-operating parts, taken on the plane of line 3-3 of Fig. 1; and Fig. 4 is an enlarged detail view of a modified form of engaging means.

In the drawings, 7 represents a car-platform pivotally mounted by a king-bolt 8 on the

bolster 9 of a four-wheeled car-truck of usual construction. Briefly, the truck comprises the pair of side bars 10, having journaled between them axles 11, carrying car-wheels 12, and connected at their middle portions by a bolster 9 and a pair of transoms 13 and at 50 their ends by end pieces 14, all in the manner now common with truck-frames for traction-cars. A pair of oppositely-extending hanger-brackets 15 are secured to the transoms 13 and have links or brake-hangers 16 pivotally 55 mounted on their upper ends and pivotally suspending the brake-shoes 17 in close relation to the tread of the car-wheels 12. Brake-levers 18 and 19, respectively, are pivoted to the brake-shoes 17 and are pivotally connected at their lower ends by a coupling-bar 20, the dead brake-lever 18 having its upper end engaging a notched stop 21, secured to one of the transoms 13, and the other (the live brake-lever 19) having its upper end pivotally 60 connected to a brake-rod 22. A coil-spring 23 serves to connect the upper ends of the two brake-levers 18 and 19 and tends to normally hold the brake-shoes 17 away from the tread of the wheels 12. The brake-rods 22 pass through 65 guide-brackets 24, which are carried by one of the end pieces 14, and pivotally connect to an arc-shaped bar 25, which is curved about the king-bolt 8 as a center and is embraced by a yoked link 26, carrying a roller 26' to bear 70 upon the inner edge thereof. The link 26 has a hook 27 pivoted in its other end and engaging with the center brake-lever 28, which is pivoted to a bracket 29 at the middle portion of the car-platform. The hook 27 engages the center 75 brake-lever 28, near the pivot thereof, and at the extreme of the other end of said center brake-lever is pivoted a brake-rod 30, containing a turnbuckle 31 and connecting with the outer end of a lever 32, which is pivoted 80 to a bracket 33, depending from the car-platform. The brake-gear as above described is duplicated at the other end of the car, the center brake-lever serving when swung from either end of the car to apply or release the 85 brakes through the connection therewith of the brake-gear of each truck, and this whatever the position of the truck may be, for

during the turning of the truck on its king-bolt 8 the arc-shaped bar 25 maintains its operative connection with the link 26.

In order to apply and release the brakes, 5 each end of the car-platform is provided with a means for forcibly throwing the lever 32 at that end of the car-platform in such a manner that the momentum of the car will serve to apply the brakes with force and still permit 10 of a quick and easy release thereof by hand operation. With this end in view each end of the car-platform is provided with an upright shaft 34, having a crank-handle 35 on its upper end and passing through the platform at its lower end and journaled in a bracket 36 beneath the platform. A locking-lever 37 is pivoted beneath the crank-handle and connects with a rod 38, having a sliding bearing in lugs on the shaft 34 to engage with 20 any of a series of perforations contained in a plate 39 on the platform, by means of which the shaft may be locked in any of its desired positions. At the lower end of the shaft 34, between the car-platform and the bracket 36, 25 is mounted a crank 40, connected to a link 41, having adjustable connection with a lever 42, which is pivoted to a bracket 43 beneath the car-platform. A link 44 connects with the free end of lever 42, and after passing through 30 a suitable guide carried by the car-platform, such as 45, it embraces by its yoked end an arc-shaped rod 46, which is also curved upon the king-bolt 8 as a center and is pivotally mounted between the longer arms of a pair of bell- 35 crank levers 47, which are pivotally supported on plates 48, secured to the front end piece 14 of the truck-frame. The bell-crank levers 47 have their pivotal connections on the plates 48 provided by means of a rod 49, which 40 connects the two plates 48 and serves to keep the two bell-crank levers 47 in pivotal alignment. The link 44 is provided with a pair of rollers 50 to bear upon the front and rear edges of the rod 46, and the yoke members 45 of said link 44 prevent the rod 46 turning therebetween. The curvature of said rod 46 serves, as in the case with rod 25, to preserve the connection between the parts carried by the car-platform and the parts carried by the 50 truck-frame during the swinging movements of the truck. Each of the shorter arms of the bell-crank levers 47 has pivoted to it an arm 51, both of said arms 51 being preferably rigidly connected to a shaft 52, extending between them and a considerable distance beyond. On each end of the shaft 52, beyond the arms 51, is rotatably mounted a sleeve 53, carrying a pair of spaced rollers 54 and 55, respectively, which are preferably of different sizes. The rollers 55 are capable of being brought into contact with the tread of the car-wheels 12 when the bell-crank levers 47 are swung to lower their shorter arms, and the rollers 54 are adapted to ride in channeled 60 bearing or track levers 56, which are pivoted

to the front end piece 14 of the truck-frame in bearings 57, provided therefor. The lower ends of said channeled levers extend below the bearings 57 and are adapted to limit the swing of the channeled levers toward the car-wheels by engaging with the front end piece 14 of the truck-frame. An arc-shaped rod 58 connects the upper ends of the two channeled levers 56 and has slidably connected thereto the yoked end of a link 59, carrying a roller 60 in its yoked portion to engage the concave edge of the rod 58, the other end of said link 59 being connected by a hook 61 to the lever 32 before mentioned.

In operation when it is desired to apply the brakes the shaft 34 is turned in its bearing by means of the crank-handle 35, so as to swing the crank 40 and the lever 42 through the link connection 41 therewith, and so produce a push upon the link 44 to cause it to swing the bell-crank levers 47 by the rod 46 connecting them and having the sliding connection with said link 44. This motion of the bell-crank levers 47 pulls down upon the arms 51 and draws the rollers 55 into engagement with the tread of the car-wheels 12. The car being in motion and the wheels thereof turning in the direction of the arrow of Fig. 1 will cause the rollers 55 to turn in the opposite direction, and as the rollers 54 are rigid with rollers 55, both being rigidly mounted on the sleeves 53, said rollers 54 are also caused to rotate in the opposite direction to the direction of rotation of the car-wheels, and as they bear upon the channeled levers 56 this rotation will cause them to travel downwardly on said channeled levers. The downward movement of the rollers 54 also brings the rollers 55 down with them, and as said rollers 55 ride on the tread of the car-wheels they produce a forward swing of the channeled levers 56, and thereby apply the brakes through the connection of the link 59 with the rod 58, carried by said channeled levers, swinging the lever 32 and through it the center brake-lever 28 by means of the brake-rod 30. To release the brakes, it is only necessary to return the shaft 34 to its original position, when the bell-crank levers 47 will be swung in the opposite direction to raise the shaft 52 and lift the rollers 55 out of contact with the car-wheels, thus permitting the coil-springs 23 to withdraw the brake-shoes 17 from the car-wheels. In order to limit the upward movement of the shaft 52, the channeled levers 56 have curved extensions 62 to engage with the sleeves 53 as the rollers 54 ride upwardly in the said channeled levers.

Secured to the transom 13, beside the plate 57, are plates 63, similar to plates 57, and in which the channeled levers 56 may be pivoted when it is desired that rollers 55 should act direct upon such channeled levers. In this arrangement the operation is the same as be-

fore described, the difference being that the brakes are more gradually applied.

With the construction of the brake-applying mechanism as above described it is apparent that the momentum of the car serves to apply the brakes with constantly-increasing force until the wheels 12 are blocked, and this is suitable for emergency purposes; but owing to the possible objection to a complete stoppage of the wheels 12 as tending to flatten the tread thereof in its general application I have further modified the construction somewhat, as shown in Fig. 4, to provide for releasing the wheel-engaging part from the brake-applying mechanism when a predetermined degree of braking force has been reached, which will be insufficient to produce a complete stoppage of the wheel. In this modified construction the roller 54 is carried by a sleeve 64, which is loosely mounted on the shaft 52 in place of the sleeve 53, and the roller 55 is carried by a separate sleeve 65, also mounted on said shaft, the two sleeves 64 and 65 having serrated ends, with their serrations held intermeshing by means of a coil-spring 66, mounted on the shaft 52 and bearing at one end against the roller 55 and at the other ends against a washer 67, fastened on the shaft 52. By this means the two sleeves 64 and 65 are held in frictional engagement with each other and normally rotate together, so that as the roller 55 is brought into engagement with the wheel 12 it will turn the roller 54 as before and cause it to ride down the channelled lever 56 and apply the brakes until the braking power has reached a predetermined extent sufficient to cause the roller 54 to offer a resistance to the turning by roller 55, which will cause the sleeve 65 to disengage its serrations from the serrations of the sleeve 64 against the pressure of the spring 66. The roller 55 will then continue its further movements independent of the roller 54, and the braking power will remain constant at that predetermined degree without completely stopping the car-wheels.

While the construction illustrated in Figs. 1 to 3 has been described as having two sets of rollers for engaging the wheel and the channelled levers, respectively, it is obvious that as they are rigidly secured to a common sleeve they, in effect, constitute a single roller, with an annular space between the two bearing-surfaces, and consequently they are together treated as a single roller in some of the claims. The same is true of the construction shown in Fig. 4, while the two sleeves are locked together by their serrations, which, as above described, is their normal condition, and therefore this construction is also included by the terms of the claims above noted, wherein a single roller is referred to.

What I claim as my invention is—

1. The combination with a wheel, of a brake therefor, a roller adapted to be brought into

engagement with the wheel to receive rotary motion therefrom, and a movable part in connection with the brake and bearing on the roller and on which the roller rides when turned by the wheel to wedge itself between the wheel-surface and the movable part and force said part to move and thereby apply the brake.

2. The combination with a wheel, of a brake therefor, a roller adapted to be brought into engagement with the wheel to receive rotary motion therefrom, and a lever in connection with the brake and bearing on the roller and on which the roller rides when turned by the wheel to wedge itself between the wheel-surface and the lever and force said lever to swing and thereby apply the brake.

3. The combination with a wheel, of a brake therefor, a roller adapted to be brought into engagement with the wheel to receive rotary motion therefrom, and a lever in connection with the brake and bearing on the roller and on which the roller rides when turned by the wheel to wedge itself between the wheel-surface and the lever and force said lever to swing and thereby apply the brake, the surface of the roller bearing on the wheel being of different diameter from the surface thereof bearing on the lever.

4. The combination with a wheel, of a brake therefor, a lever having connection with the brake, a shaft movable between the lever and the wheel, a roller on the shaft adapted to bear on the wheel, and a second roller on the shaft bearing on the lever and adapted to be turned by the first-named roller when said roller is brought into bearing with the wheel and thereby be caused to ride on the lever to wedge the shaft between the wheel and the lever and cause said lever to swing and apply the brake.

5. The combination with a wheel, of a brake therefor, a lever having connection with the brake, a shaft movable between the lever and the wheel, a sleeve loosely mounted on the shaft, a roller on the sleeve bearing on the lever, and a second roller on the sleeve adapted to bear on the wheel and be rotated thereby to rotate the first-named roller and cause it to ride on the lever and force the shaft to wedge between the lever and the wheel and thereby swing the lever to apply the brake.

6. The combination with a wheel, of a brake therefor, a lever having connection with the brake, a shaft movable between the lever and the wheel, a roller carried by the shaft bearing on the lever, and means for moving the shaft to bring the roller into engagement with the wheel and cause it to rotate and thereby ride on the lever and wedge the shaft between the lever and wheel requiring the lever to swing and apply the brake.

7. The combination with a car-truck, of a pair of bell-crank levers pivoted to the truck-frame, a pair of track-levers also pivoted to

the truck-frame, a pair of arms pivoted on the bell-crank levers, a shaft carried by the pair of arms, rollers carried by the shaft bearing on the track-levers, a brake-gear connected with the track-levers, and means for swinging the bell-crank levers to move the rollers into bearing with the truck-wheels whereby said rollers are caused to rotate and ride on the track-levers to wedge the shaft between the wheels and the track-levers and so cause the track-levers to swing and apply the brake.

8. The combination with a pivoted car-truck and its platform, of a pair of bell-crank levers pivoted to the truck-frame, an arc-shaped bar 15 pivotally connected to the outer ends of said bell-crank levers, a link having a guide-support from the platform and slidably engaging the arc-shaped bar, a pair of track-levers also pivoted on the truck-frame, a pair of 20 arms pivoted to the inner ends of the bell-crank levers, a shaft carried by the pair of arms, rollers carried by the shaft bearing on the track-levers, a brake-gear connected with the track-levers, and means for moving the link to swing the bell-crank levers and cause them to move the rollers into bearing with the truck-wheels whereby said rollers are caused to rotate and ride on the track-levers to wedge the shaft between the wheels and 25 the track-levers and so cause the track-levers to swing and apply the brakes, the arc-shaped bar serving to maintain the operative connection between the link and the bell-crank levers during the pivotal movements of the truck.

9. The combination with a pivoted car-truck and its platform, of a pair of bell-crank levers pivoted to the truck-frame, an arc-shaped bar 30 pivotally connected to the outer ends of said bell-crank levers, a link having a guide-support from the platform and slidably engaging the arc-shaped bar, a pair of friction-rollers carried by the link to receive the arc-shaped bar between them, a lever pivoted to the platform and having connection with the link, a shaft journaled in the platform and having a crank and link adjustable connection with the lever, a crank-handle on the shaft, means in connection therewith for locking the shaft in its several positions, a pair of track-levers 40 also pivoted on the truck-frame, a pair of arms pivoted on the inner ends of the bell-crank levers, a shaft carried by the pair of arms, rollers mounted on the shaft and bearing on the track-levers, and a brake-gear connected with the track-levers, said bell-crank levers being adapted to be swung by the operation of the crank-handle to move the rollers into bearing with the truck-wheels whereby 45 said rollers are caused to rotate and ride on the track-levers to move said track-levers and apply the brakes.

10. The combination with a pivoted car-truck and its platform, of a pair of bell-crank 50 levers pivoted to the truck-frame, an arc-

shaped bar pivotally connected to the outer ends of said bell-crank levers, a link having a guide-support from the platform and slidably engaging the arc-shaped bar, a pair of track-levers also pivoted on the truck-frame, 70 a pair of arms pivoted on the inner ends of the bell-crank levers, a shaft carried by the pair of arms, rollers mounted on the shaft bearing on the track-levers, an arc-shaped bar connecting the track-levers, a brake-lever 75 pivoted to the car-platform having a sliding-link connection with the arc-shaped bar of the track-levers, a center brake-lever pivoted to the car-platform, a brake-rod connecting the center brake-lever with said brake-lever, a 80 pair of brake-shoes suspended between the wheels on each side of the truck, brake-levers pivoted thereto, coupling-bars connecting the brake-levers, springs also connecting the brake-levers, a stop for one brake-lever on each 85 side of the truck, a brake-rod connected to the other brake-lever on each side of the truck, an arc-shaped bar connecting the brake-rods, guides on the truck-frame for supporting the brake-rods, a sliding-link connection between 90 said arc-shaped bar of the brake-rods and the center brake-lever, and means for moving the link which is in connection with the arc-shaped bar of the bell-crank levers to cause said bell-crank levers to bring the rollers into 95 engagement with the truck-wheels to receive motion therefrom and impart motion to the track-levers to apply the brakes.

11. The combination with a wheel, of a brake therefor, a lever having connection with the 100 brake, and a roller bearing on the lever and adapted to be brought into bearing with the wheel to receive motion therefrom and be caused to ride upon the lever to swing said lever and apply the brake, said roller being 105 formed in two parts normally locked together so that the turning of one part by the wheel will cause the other part to turn and ride on the lever but capable of becoming unlocked when the braking power has reached a predetermined degree and so permit the part in engagement with the wheel to rotate independently of the other part.

12. The combination with a wheel, a brake therefor, a lever having connection with the 110 brake, a shaft, a roller mounted thereon and bearing on the lever, another roller mounted on the shaft adapted to be brought into bearing with the wheel, and means for maintaining an engagement between the two rollers 115 until the rotary movements given to one roller by the wheel have been imparted to the other roller to cause it to ride on the lever and apply the brakes to a predetermined extent and then releasing the engagement between the 120 rollers.

13. The combination with a wheel, of a brake therefor, a lever having connection with the 125 brake, a shaft, a roller mounted thereon and bearing on the lever, and another roller mount- 130

ed on the shaft and having frictional engagement with the first-named roller, the latter-named roller being adapted to be brought into engagement with the wheel to cause the rotation of the first-named roller and produce the application of the brake thereby, such frictional engagement becoming ineffective when the brake has been applied to a predetermined degree.

10 14. The combination with a wheel, of a brake therefor, a lever having connection with the brake, a shaft, a sleeve loosely mounted on the shaft, a roller on the sleeve bearing on the lever, a second sleeve loosely mounted on the shaft and having a serrated end adapted to intermesh with a serrated end of the first-named sleeve, a roller on the second sleeve adapted to be brought into engagement with

the wheel, and a coil-spring seated on the shaft and pressing the two sleeves together 20 to produce a frictional engagement between them and cause the rotation of the second-named roller when in contact with the wheel to produce a rotation of the first-named roller and cause it to ride on the lever and force said 25 lever to swing and apply the brakes until the resistance of the first-named roller is sufficient to cause the second-named roller to overcome the pressure of the spring and rotate independently of the first-named roller. 30

In testimony whereof I affix my signature in presence of two witnesses.
